Primary Examiner — Dana K Weiland*Assistant Examiner* — JennyLou M Binas(74) *Attorney, Agent, or Firm* — Warner Norcross + Judd LLP(57) **CLAIM**

The ornamental design for a vacuum cleaner, as shown and described.

DESCRIPTION

FIG. 1 is a front perspective view of a vacuum cleaner showing our new design;

FIG. 2 is a front view thereof;

FIG. 3 is a left side view thereof;

FIG. 4 is a right side view thereof;

FIG. 5 is an enlarged top view of the vacuum cleaner;

FIG. 6 is an enlarged front perspective view of a lower portion of the vacuum cleaner shown in FIG. 1; and,

FIG. 7 is an enlarged front view of a lower portion of the vacuum cleaner shown in FIG. 2.

The details of the vacuum cleaner shown in broken lines form no part of the claimed design.

1 Claim, 7 Drawing Sheets(56)
